UNITED STATES PATENT OFFICE

117,280

DESIGN FOR A PASTRY CRUST

Bernard Lambers, Oak Park, Ill., assignor to Lloyd
J. Harriss, Kenilworth, Ill.

Application August 15, 1939, Serial No. 86,698

Term of patent 14 years

To all whom it may concern:

Be it known that I, Bernard Lambers, a citizen of the United States, residing at Oak Park, in the county of Cook and State of Illinois, have invented a new, original, and ornamental Design for a Pastry Crust, of which the following is a specification, reference being had to the accompanying drawing, forming part thereof.

In the drawing:

I claim:

The ornamental design for a pastry crust, as shown.

BERNARD LAMBERS.
